Attorneys.

UNITED STATES PATENT OFFICE

FRANK P. FOULKE, OF INDIANAPOLIS, INDIANA, ASSIGNOR OF FORTY-NINE PER CENT
TO THOMAS E. GRINSLADE, OF INDIANAPOLIS, INDIANA

RADIO AERIAL BRACKET

Application filed January 30, 1929. Serial No. 336,057.

The object of this invention is to provide a radio aerial support which will be cheap to manufacture, which may be quickly and easily clamped to an eave, window sill, chimney or parapet of a private dwelling, or an apartment house without injury to the building and which will be neat in appearance, durable, and removed as easily and quickly as it was installed.

10 I accomplish the above and other specific objects which will hereinafter appear, by the mechanism illustrated in the accompanying drawing, in which—

Fig. 1 is a side elevation of my invention assembled for use but not applied to a building.

Fig. 2, is a view of the device of Fig. 1, looking at it from the right of that drawing.

Fig. 3, shows the device of Fig. 1, applied to a gable roof at the comb.

Fig. 4, shows the device applied to the parapet of an apartment house; and

Fig. 5, illustrates the application to the eave of a sloping roof.

25 Like characters of reference indicate like parts in the several views of the drawing.

The body of the support comprises a post 6, having an arm 7 at one end preferably at right angles, and a V-shaped jaw 8 at the other end extending in the same direction.

30 The structure is preferably formed out of channel iron or steel with the channel on the inner side.

The post 6, has a series of equidistant holes 18, here shown as four in number, to receive two bolts 9, 9, by which a slotted arm 10, of a clamp-jaw 11, is bolted to the post 6. The extra holes are for adjustment of the jaw 11 on the post 6.

40 The post 6 also has a threaded hole for the attachment of the threaded end, of a bolt 12 on the outer end of which is an insulator head 13.

The arm 7 has a threaded hole through which is screwed a threaded bolt 14 until it contacts the jaw 11 and by which bolt the jaw 8 may be moved to clamp the support between the two jaws 8 and 11.

45 On the outer end of the bolt is a lead-in insulator head 15. The aerial 16 is fastened

to the two insulator heads in the manner shown in the drawing. The lead-in insulator 15 may be attached at the bottom one of the four holes primarily designed to receive the bolts 9, and if the strain on the aerial 55 is away from the object to which my device is clamped it is advisable to so move the insulator 15.

The inner end of the bolt 14 is preferably conical and a conical depression is formed 60 as a seat for it in the jaw 11. The slot in arm 10 and series of holes in post 6, afford considerable adjustment for jaw 11, and the final tightening is by bolt 14.

The jaw 8 is made V-shape so it will pass 65 around gutters and copings and hook more securely into supporting structures, some of which are illustrated in the drawing.

Having thus fully described my invention what I claim as new and wish to secure by 70 Letters Patent is:

1. A radio aerial bracket comprising a body member having an arm at one end and a jaw at the other, a jaw member located between the arm and jaw of the body member 75 and adjustably secured to the body member, a threaded bolt screwing through the arm into contact with the adjustable jaw and an aerial insulator attached to the outer end of the bolt.

2. A radio aerial bracket comprising a body member having a series of holes and having a lateral arm at one end and a lateral jaw member on the same side at the other end, and a longitudinally slotted member, bolts passing through the slot and through holes of the body member to adjustably secure the slotted member to the body member, said slotted member having a lateral jaw parallel and cooperating with 80 the jaw of the body member, a threaded bolt screwing through the arm into contact with the adjustable jaw, and an aerial insulator attached to the outer end of the bolt.

3. A radio aerial bracket comprising a 85 body member having an arm at one end and a V-shaped jaw at the other, a jaw member adjustably bolted to the body member between the arm and jaw of the body member, a lead-in insulator movably secured to 100

the body member, a threaded bolt screwed through the arm into contact with the adjustable jaw and an aerial insulator attached to the outer end of the bolt.

5 In testimony whereof I affix my signature.

FRANK P. FOULKE.
